UNITED STATES PATENT OFFICE

JOSEPH SAUER, OF HOLLIS, NEW YORK

FOLDING TABLE

Application filed September 8, 1928. Serial No. 304,727.

The invention relates to folding tables and has for its object to provide a table of the type indicated, with a novel and simple locking means, whereby the legs or equivalent supporting means are securely locked in their unfolded supporting positions and maintained with equal efficiency in their folded inoperative positions.

A further object of the invention is to construct the aforesaid locking means in a manner to provide a maximum of rigidity in the table when the latter is set up for use.

Other more specific objects will appear from the description hereinafter, and the features of novelty will be pointed out in the claims.

Reference is to be had to the accompanying drawing, which illustrates an example of the invention without defining its limits, and in which Fig. 1 is a fragmentary section of a table equipped with the improved arrangement; Fig. 2 is an end view thereof; Fig. 3 is a detail elevation partly in section of the novel locking means, and Fig. 4 is an inverted plan view thereof.

As shown in the drawings, the table comprises the customary top 10, which may be of any conventional type, and supporting means foldably connected with said top and adapted to be adjusted to operative supporting positions, and to folded inoperative positions, as will appear more fully hereinafter.

In the illustrated example, the supporting means comprises legs 11 connected together in pairs in any suitable manner, as, for instance, by means of transverse members 12, as illustrated in Figs. 1 and 2; each pair of legs 11 is pivotally connected with the top 10, for instance, by being hinged thereto at 12, the arrangement being such that in their operative supporting positions each pair of legs 11 extends in vertical directions beneath the top 10 and in perpendicular relation thereto, the upper ends of the legs 11 and the upper edges of the transverse members 12 forming shoulders which engage the lower surface of the top to firmly support the same.

The novel locking means whereby the legs 11 or their equivalent are firmly locked in

their operative supporting positions, and also fixed in their folded positions, is duplicated with respect to each pair of legs, and in each instance consists of members 13 located in spaced parallel relation to each other upon the bottom surface of the top 10 and provided with complementary guide slots 14, extending lengthwise of the members 13 and terminating at their opposite ends in closed transverse extensions which constitute seats 15 and 15^a respectively, the purpose of which will appear more fully hereinafter. The members 13 may comprise separate elements independently secured to the table top 10 in proper relation to each other, or, as preferred, said members 13 may form part of a unit and comprise integral parts of a plate 16 from which said members 13 depend, as shown in the drawings. In such case, the plate 16 is secured to the top 10 by suitable fastening devices, such as screws 17, and constitutes the medium whereby said members 13 are fastened in place. Each locking means further includes a slideable device which, in the illustrated example, is shown in the form

of a pin 18 extending through the slots 14, so as to be slideable lengthwise thereof and bridging the spaces between the members 13, as shown in Fig. 2. The pin 18 or its equivalent is connected with the legs 11 of a given pair or their equivalent, for instance, by means of braces 19 which at one end are pivoted at 20 to each of the legs 11, and at the other end are pivotally connected with the pin 18 so as to be capable of pivotal movement relatively thereto; for the purpose of increasing the rigidity of the structure, the braces 19 are preferably in slideable surface engagement with the exterior faces of the members 13.

In the preferred arrangement, means is provided whereby the pin 18 or its equivalent is removably maintained in at least the seat 15, which receives said pin when the legs 11 or their equivalent are in their unfolded supporting positions. In the illustrated example the means in question consists of a leaf spring 21, adapted to exert an upward pressure on the pin 18, and preferably having its free end projected downwardly, as

indicated at 22; the spring 21 may be secured in place upon the bottom surface of the top 10 in any convenient manner, for instance, by being riveted to an extension 16^a of the plate 16. In addition to the parts so far described, the improved arrangement includes means for facilitating the withdrawal of the slideable device or specifically the pin 18 from the seats 15 and 15^a when it is desired to adjust the legs 11 to and from their several positions; in the illustrated example, the means referred to comprises a handle 23 suspended from and connected with the pin 18 and occupying a readily accessible position, as shown in Figs. 1, 2 and 3.

In the drawings, the table is shown in its unfolded condition, that is, set up for use, in which position the legs 11 extend vertically beneath the top 10 with the pins 18 located in the seats 15 and thereby fixing the braces 19 rigidly in angular relation to each pair of legs 11; the latter are accordingly prevented from developing any pivotal movement on the hinges 12, as any tendency to such movement will be communicated to the braces 19, and will be resisted by the pins 18 in co-operation with the seats 15, as will be obvious. The springs 21 or their equivalent serve to yieldingly maintain the pins 18 in the seats 15 against any unintentional displacement. When it is desired to knock down the table, the pins 18 or their equivalent are withdrawn from the seats 15 against the tension of the springs 21, which may be readily accomplished for instance by exerting pressure in the proper direction upon the braces 19; preferably, however, a downward pull is exerted upon the handles 23 to overcome the tension of the springs 21 and to thereby effect the removal of the pins 18 from the aforesaid seats. In any case, as soon as the pins 18 are out of the seats 15, they are in position to travel lengthwise of the slots 14 to thereby permit the legs 11 to pivotally swing upon the hinges 12 into folded positions beneath the table top 10; in the completely folded position of the legs 11, the pins 18 will enter the seats 15^a and thus will automatically maintain said legs in their inoperative folded positions until it is again desired to set up the table for use. If desired, the springs 21 may be duplicated at the opposite ends of the members 13 in positions to yieldingly maintain the pins 18 in the seats 15^a in the same way as said pins are maintained in the seats 15. When use of the table is desired, the pins 18 are simply withdrawn from the seats 15^a, for instance, by means of the handles 23 and moved lengthwise of the slots 14 in the opposite direction, until they finally come into engagement with the ends 22 of the springs 21; a continued movement of said pins 18 in the slots 14 will cause the springs 21 to be depressed until the pins come into

registry with the seats 15, whereupon tension of the springs 21 will automatically snap the pins into said seats 15 and yieldingly maintain them therein until the table is again to be knocked down and folded up. With the arrangement set forth, the locking means is of very simple construction, and when made in the form of a unit, as in the illustrated example, is easily and quickly attached at the proper points to the table top 10. The locking means serves to firmly fix the legs 11 or their equivalent in their unfolded operative positions, so that the table is supported thereon with a maximum of rigidity and without any appreciable vibration or swaying. By providing the spaced members 13 and the slots 14 therein, and by having the pins 18 or their equivalent bridge the spaces between said members 13, said pins are in engagement only with the edges of the slots 14, which as shown, may be of minimum width; as a result of this, the points at which friction between the pins and the members 13 is developed, are represented by the points of engagement between the pins 18 and the aforesaid edges of said slots 14, said friction being accordingly maintained at the lowest possible point. Resistance to the operation of the locking means and wear upon the pins 18 is thus reduced to a minimum, and the locking means does not easily loosen up and become inefficient.

The nature and construction of the novel mechanism illustrated and described herein, is such that it may readily be incorporated in existing types of folding table, or substituted for other less efficient means which may be present therein. The mechanism requires no particular skill or effort in its manipulation and may be easily operated by anyone.

Various changes in the specific form shown and described may be made within the scope of the claims without departing from the spirit of the invention.

I claim:—

1. A folding table comprising a top, supporting legs connected together in pairs and hinged to said top, locking means for each pair of legs secured to said top and consisting of two spaced parallel members provided with guide slots extending lengthwise thereof, said slots terminating at their opposite ends in transverse closed extensions constituting seats, a pin extending through said slots and bridging the space between said members, braces extending between said pin and each one of the legs of a given pair and connected therewith, said pin being slideable lengthwise of said slots and into said seats to adjust said pair of legs from unfolded supporting to folded non-supporting positions and vice versa and to fix them therein, a spring located between said parallel members and engaging said pin for yieldingly press-

ing said pin into one of said seats to lock said pair of legs in its supporting position, and a handle pivotally connected with said pin for withdrawing the latter from said seat against the tension of said spring to permit said pair of legs to be adjusted to its folded non-supporting position.

2. A folding table comprising a top, supporting legs connected together in pairs and hinged to said top, locking means for each pair of legs secured to said top and consisting of two spaced parallel members provided with guide slots extending lengthwise thereof, said slots terminating at their opposite ends in transverse closed extensions constituting seats, a pin extending through said slots and bridging the space between said members, braces extending between said pin and each one of the legs of a given pair and connected therewith, said pin being slidable lengthwise of said slots and into said seats to adjust said pair of legs from unfolded supporting to folded non-supporting positions and vice versa and to fix them therein, a spring located between said parallel members adjacent to one of said seats for yieldingly pressing said pin into the same to lock it therein and a handle pivotally connected with said pin whereby the removal thereof from said seats is facilitated to permit said pair of legs to be pivotally adjusted relatively to said top.

3. A folding table comprising a top, supporting means foldably connected with said top, parallel members secured to said top and located in spaced relation to each other, said members being provided with complementary slots terminating at their opposite ends in closed seats, a slidable device connected with said supporting means and bridging the space between said members, said slidable device being movable lengthwise of said slots and into said seats to pivotally adjust said supporting members relatively to said top and to lock them in their folded and unfolded positions, and a handle pivotally connected with said device for facilitating the withdrawal thereof from said seats.

In testimony whereof I have hereunto set my hand.

JOSEPH SAUER.
